UNITED STATES PATENT OFFICE.

PETER COOPER HEWITT, OF RINGWOOD MANOR, NEW JERSEY, ASSIGNOR, BY MESNE ASSIGNMENTS, TO COOPER HEWITT ELECTRIC COMPANY, OF HOBOKEN, NEW JERSEY, A CORPORATION OF NEW JERSEY.

VAPOR ELECTRIC LAMP AND CONNECTIONS.

1,110,559.

Specification of Letters Patent. Patented Sept. 15, 1914.

Original application filed March 19, 1903, Serial No. 148,504. Divided and this application filed January 10, 1912. Serial No. 670,358.

To all whom it may concern:

Be it known that I, PETER COOPER HEWITT, a citizen of the United States, and resident of Ringwood Manor, county of Passaic, State 5 of New Jersey, have invented certain new and useful Improvements in Vapor Electric Lamps and Connections, of which the following is a specification.

The present invention relates to an electrical apparatus in which a suitable gas or vapor inclosed in a transparent container is made luminous by the passage of electric current. The type of apparatus illustrated is adapted for various uses, and the novel 15 features of the said device will be explained in the specification and fully set forth in the claim.

The illustrations, Figures 1 and 2, show similar types of electrical apparatus of this 20 sort, the main difference appearing in the electrical connections for the lamp.

The container consists of a tube, 1, of glass or other transparent material, provided with electrodes, 2, 3, and 4. The 25 electrode 2 is here shown as a body of solid conducting material such as iron, while the electrodes 3 and 4 appear as small masses of mercury. Any suitable materials may be substituted for those named. The electrodes 2 and 4 are mounted at the opposite ends of the tube 1, and the electrode 3 is contained in a small pocket, 5, formed on the container 1 about midway of its length. The device is provided with a chamber 6 30 at the top serving as a cooling or condensing chamber whereby the vapors formed in the operation of the lamp are condensed and the general capacity of the device for radiating heat is increased.

40 In Fig. 1, the electrodes 2 and 3 are connected with the positive side of an electric circuit and the electrode 4 with the negative side. In Fig. 2, the electrode 2 is positive and the electrodes 3 and 4 are negative. 45 I may interpose suitable resistances or inductance devices, 7 and 8, in the wires leading to the electrodes, as may be desired or required for different uses of the apparatus and for steadyng the operation thereof.

50 In the lamp illustrated in Fig. 2, it is

found that the vapor in the lower part of the lamp is denser than in the upper part, the quantity of current passing through the said lower half being approximately double that passing through the upper half. The 55 apparatus may be used in testing the operations which take place in an inclosed gas or vapor carrying electric current, or it may be utilized for producing different effects in different parts of a single inclosing chamber. 60

Fig. 2 is made use of simply to illustrate a different set of connections for the electrodes, and it will be understood that these connections may be still further varied to suit different requirements, at the will of 65 the operator.

In operating this lamp the mercury which is condensed in the chamber 6 is redistributed for condensation, passing down the tube into the pocket 5 and overflowing from 70 that pocket into the lower part of the tube and there reconstructing the electrode 4. This is found to be a valuable feature of the lamp and is one of the features constituting the present invention. 75

This application is a division of my application filed March 19th, 1903, Serial Number 148,504; issued on January 16, 1912, as Patent Number 1,014,705, and a companion to my application filed July 11th, 1911, 80 Serial Number 637,951, issued on January 16, 1912 as Patent Number 1,014,965, which is also a division of the first named application.

I claim as my invention

85 A vapor electric device comprising a vertical tubular portion, a condensing chamber at the top thereof, a solid anode within the said chamber and a plurality of vaporizable cathodes disposed at intervals within the 90 vertical tube, the said vaporizable electrodes being connected together outside the tube.

Signed at New York in the county of New York and State of New York this 8th day of January A. D. 1912.

PETER COOPER HEWITT.
